UNITED STATES PATENT OFFICE.

MARTIN E. THOMAS, OF AUBREY, TEXAS, ASSIGNOR OF ONE-FOURTH TO JOHN L. FRIES, ONE-FOURTH TO WILL E. FRIES, ONE-EIGHTH TO LONNIE D. HEFNER, ALL OF TIOGA, TEXAS, AND ONE-FOURTH TO CLAUD W. HOPPER, OF AUBREY, TEXAS.

DRILL BIT.

1,402,684.

Specification of Letters Patent.

Patented Jan. 3, 1922.

Application filed February 26, 1921. Serial No. 448,049.

To all whom it may concern:

Be it known that I, MARTIN E. THOMAS, a citizen of the United States, residing at Aubrey, in the county of Denton and State of Texas, have invented certain new and useful Improvements in a Drill Bit, of which the following is a specification.

The invention relates to improvements in drill bits, and more particularly to a type of the same adapted for use in the boring or drilling of oil wells, and the like.

The primary object of the invention is to provide for a device of the character mentioned, and one of a nature admitting of the placing and driving of sections of the well casing downward of the drilled bore simultaneously with the boring or drilling operation, and the ready withdrawal or replacement of the drill bit upward or downward through the placed sections of the casing at any time during such boring or drilling operation, or at the conclusion thereof.

A further object of the invention is to provide for a drill bit of the class described, and one embodying features of automatic expansion and contraction of certain of the cutting elements thereof depending upon the direction of the rotation of same, or of its insertion into and withdrawal from a partially drilled or cased bore.

With the foregoing and other objects in view, the invention resides in the certain novel and useful construction and arrangement of parts as will be hereinafter more fully described, set forth in the appended claims, and illustrated in the accompanying drawings, in which:

Fig. 1 is a side elevation of the drill bit in operative position within the lower end of a well casing section, the latter being in cross section,

Fig. 2 is a view similar to that of Fig. 1 with the drill bit turned a quarter revolution from its position in the latter,

Fig. 3 is a bottom plan view of the drill bit, and the adjacent end of a well casing section with the cutters of the former in operative or expanded position, the parts being relatively arranged as in Fig. 1, and,

Fig. 4 is a view similar to Fig. 3, but showing the cutters of the drill bit in inoperative or contracted position.

Referring to the drawing, wherein similar characters of reference designate corresponding parts in the several views thereof,

the numeral 10 indicates a drill shank of a suitable weight of metal, preferably circular in cross section, for a major portion of its length and gradually increasing in diameter at its lower end to provide an enlarged head portion 11. The enlarged head portion 11 has its end face formed to provide pairs of connected angularly disposed plane faces 12-12' and 13-13', the upper angular faces 12 and 13 of each pair of faces being reversely disposed one diametrically opposite the other with their upper edges aligning on the mean diameter of the head portion and their lower ends connecting the lower angular faces 12' and 13' which incline laterally therefrom, and are also disposed one diametrically opposite the other, both angular faces of each pair of such faces being outwardly and downwardly inclined or bevelled, as shown.

Spaced above and extending parallel to the angular faces 12' and 13' of each pair of the angularly disposed plane faces and of slightly less area with respect thereto are a pair of angularly disposed integral portions or ears 14 and 15, respectively, at the inner sides of which are formed shoulder portions 16 and 17, the walls of which shoulder portions curve outwardly from parts immediately adjacent the longitudinal center of the bit, and into the periphery of the head portion 11. Formed in the integral portions or ears 14 and 15 are slots 18 and 19, respectively, which extend on lines approximating chords of the circles formed by the peripheral wall of the head portion of the bit shank.

Mounted on the angularly inclined faces 12 and 13 are a pair of circular cutters 20 and 21, respectively, the same being free for rotation on fixed journal pins 22, which are so positioned as to have their peripheral edges rotated within the curvature of the peripheral wall of the head portion of the bit shank. A pair of rotary cutters 23 and 24 are journaled on bolts 25, one of which is slidably engaged in the slot 18 of the ear 14, and the other similarly engaged in slot 19 of the ear 15. By reason of the radial and chordal inclination of the ears 14 and 15, and consequently of the slots 18 and 19, the bolts 25 normally rest in the outer lower end of the latter, so that the peripheral edges of the cutters 23 and 24 are retracted to positions within the confines of the circle de-

fined by the peripheral wall of the head portion 11, while the bolts 25 move to the upper opposite ends of the slots 18 and 19 for projecting goodly portions of the peripheral edges of the cutters 23 and 24 outwardly of the peripheral wall of the head portion 11, when the bit is placed in operative position and rotated in the desired clockwise direction.

- 10 In the use of the drill bit thus provided, the same is to be operatively connected to any suitable power mechanism, and directed end-on against the ground surface where it is desired to drill a well. In the present 15 construction, the drill bit is operative when rotated in a clock-wise direction, when the engagement with the ground will cause the movable cutters 23 and 24 to project outward of the periphery of the head portion 20 with their journal pins or bolts at the inner upper ends of the slots 18 and 19, in which position these cutters determine the full diameter of the bore to be drilled, while the fixed cutters 20 and 21 cut away the central 25 portion of the bore, the cut or loosened soil being directed from both sets of cutters upward through the inclined slot-ways or recesses formed between the opposed faces of the angular faces 12' and 13' of the head portion 11 and the ears 14 and 15.

It is particularly desired in the use of this drill bit for drilling oil wells and the like, to have a casing section placed in the bore of the well after the same has been formed to 35 a suitable depth, and other casing sections may be connected to the first positioned section and driven home into the bore correspondingly with its increased depth. If for any reason it becomes necessary to withdraw 40 the drill bit from the bore of the partially drilled and encased well, the upward pull of the drill bit causes the cutters 23 and 24 to be freed from contact with the wall of the bore by the bolts 25, carrying the same, tending to move downwardly of the slots 45 18 and 19 for the retraction of these cutters backward and inward of the peripheral wall of the head portion 11 of the bit shank, when the bit may be readily withdrawn upward of 50 the bore of the well and of the casing sections, the latter being designated at 26 of the drawings, the diameter of the head portion 11 of the bit shank 10 being substantially less than that of the casing sections. 55 In the re-insertion of the drill bit into the casing, the movable cutters 23 and 24 will slide freely along the surface thereof until the lower end thereof is reached, when they will again be projected to the full diameter 60 of the well bore for further operation.

Having thus fully described the invention, what is claimed, is:—

- 65 1. A drill bit comprising a bit shank, a plurality of rotary cutters angularly mounted on the working end of the bit

shank, and means admitting of certain of the cutters moving outwardly of the bit shank—to cutting position outwardly of the side wall thereof when the bit is rested on the bottom of the bore and turned in one direction, the cutters being withdrawn from cutting position by turning the bit in the opposite direction.

2. A drill bit comprising a bit shank, 75 rotary cutters fixedly and angularly mounted on the working end of the bit shank, and certain other rotary cutters angularly mounted for movement outwardly of the bit shank—to cutting position, outwardly of the side wall thereof when the bit is rested on 80 the bottom of the bore and turned in one direction, the cutters being withdrawn from cutting position by turning the bit in the opposite direction.

3. A drill bit comprising a shank portion 85 and an enlarged head portion formed to provide a plurality of angularly disposed plane faces, rotary cutters fixedly mounted on certain of the inclined faces of the head portion, and certain other rotary cutters 90 mounted for movement outwardly of the bit shank—to cutting position outwardly of the side wall thereof when the bit is rested on the bottom of the bore and turned in one direction, the cutters being withdrawn from 95 cutting position by turning the bit in the opposite direction.

4. A drill bit comprising a shank portion and an enlarged head portion formed to provide a plurality of angularly disposed plane 100 faces, rotary cutters fixedly mounted on certain of the inclined faces of the head portion, and certain other rotary cutters alternately mounted for movement outwardly of the bit shank—to cutting position outwardly 105 of the side wall thereof when the bit is rested on the bottom of the bore and turned in one direction, the cutters being withdrawn from cutting position by turning the bit in the opposite direction.

5. A drill bit comprising a cylindrical shank portion and an enlarged cylindrical head portion formed to provide a plurality of correspondingly inclined plane faces, rotary cutters fixedly mounted on certain 115 of the inclined faces of the head portion, and certain other rotary cutters alternately mounted for movement outwardly of the bit shank—to cutting position outwardly of the side wall thereof when the bit is rested on 120 the bottom of the bore and turned in one direction, the cutters being withdrawn from cutting position by turning the bit in the opposite direction.

6. A drill bit comprising a cylindrical 125 shank portion and an enlarged cylindrical head portion formed to provide a plurality of correspondingly inclined faces, alternately arranged inclined faces being under-cut to provide correspondingly inclined material 130

directing slot-ways, rotary cutters fixedly mounted on certain of the inclined faces of the head portion, and certain other rotary cutters mounted on the alternately arranged 5 inclined faces for movement outwardly of the bit shank—to cutting position outwardly of the side wall thereof when the bit is rested on the bottom of the bore and turned in one direction, the cutters being withdrawn from 10 cutting position by turning the bit in the opposite direction.

7. A drill bit comprising a drill shank having its working end formed to provide a series of angularly inclined plane faces correspondingly arranged in a chordal direction thereof, alternate faces of a series of such faces being undercut to provide material directing slot-ways, fixed rotary cutters mounted on certain of the faces inwardly 20 of the side wall of the drill shank, chordally arranged slot-ways formed in the other of said faces, and rotary cutters mounted in said last mentioned slot-ways for the movement of the cutting edges thereof outward 25 of the side wall of the drill shank when operated.

8. A drill bit comprising a drill shank having its working end formed to provide a series of angularly inclined plane faces correspondingly arranged on chordal lines thereof, alternate faces of a series of such faces being undercut to provide material 30 directing slot-ways, extending in planes parallel to the plane faces complementary thereto, fixed rotary cutters mounted on certain of the faces inwardly 35 of the side wall of the drill shank, slot-ways extending transversely of the other of said faces and on chordal lines with respect to the drill shank, and rotary cutters mounted in said 40 shank, and rotary cutters mounted in said last mentioned slot-ways for the movement of the cutting edges thereof outward of the side wall of the drill shank when operated.

9. A drill bit comprising a drill shank of 45 circular cross section and tapered in a for-

ward direction to provide an enlarged working end portion, the working end portion being formed to provide a series of angularly inclined plane faces correspondingly arranged on chordal lines thereof, alternate 50 faces of a series of such faces being undercut to provide material directing slot-ways extending in planes parallel to the plane faces complementary thereto, fixed rotary cutters mounted on certain of the faces inwardly of 55 the side wall of the drill shank, slot-ways extending transversely of the other of said faces and on chordal lines with respect to the drill shank, and rotary cutters mounted in said last mentioned slot-ways for the 60 movement of the cutting edges thereof outward of the side wall of the drill shank when operated.

10. A drill bit having a plurality of rotary cutters mounted on the working end thereof, certain of said cutters being mounted for movement outwardly of the bit to cutting position outwardly of the side wall thereof when the bit is rested on the bottom of the bore and turned in one direction, the cutters 70 being withdrawn from cutting position by turning the bit in the opposite direction.

11. A drill bit having its working end formed to provide a plurality of plane faces each extending from the center to the circumference and downwardly and forwardly inclined relative to the axis thereof, and a rotary cutter mounted on each of the said plane faces, certain of said cutters being mounted for movement outwardly of the bit 75 to cutting position outwardly of the side thereof when the bit is rested on the bottom of the bore and turned in one direction, the cutters being withdrawn from cutting position by turning the bit in the opposite 80 direction.

In testimony whereof, I affix my signature hereto.

MARTIN E. THOMAS.
